[57] CLAIM

The ornamental design for a wall mounted storage cabinet, as shown and described.

DESCRIPTION

FIG. 1 is a perspective view of a wall mounted storage cabinet showing my new design, the broken lines being for illustrative purposes only;

FIG. 2 is an enlarged front elevational view thereof, with the door open;

FIG. 3 is an enlarged front elevational view thereof, the rear being unornamented;

FIG. 4 is an enlarged right side elevational view thereof, the side opposite being a mirror image;

FIG. 5 is an enlarged top plan view thereof, the bottom being a mirror image.
